UNITED STATES PATENT OFFICE.

BARRETT CLAUD. OBLINGER AND ALBERT HENRY CLAY BEATTY, OF INDEPENDENCE, MISSOURI.

HEAT-REFLECTOR.

SPECIFICATION forming part of Letters Patent No. 794,041, dated July 4, 1905.

Application filed July 26, 1904. Serial No. 218,054.

To all whom it may concern:

Be it known that we, BARRETT CLAUD. OBLINGER and ALBERT HENRY CLAY BEATTY, citizens of the United States, residing at Independence, in the county of Jackson and State of Missouri, have invented a new and useful Heat-Reflector, of which the following is a specification.

This invention relates to heat-reflectors for stoves; and it may be described as an improvement on the device for which Letters Patent of the United States No. 706,996 were granted to us on the 12th day of August, 1902.

The object of this invention, as in the case of the patent above referred to, is to cause the gases rising from the fire to be consumed within the stove instead of passing out of the chimney and also to reflect downwardly and outwardly the heat generated by such combustion of the gases.

In our aforesaid patent the objects of the invention were accomplished by placing an annular reflector having downwardly-converging sides in the top of the stove and by arranging underneath the same a vertically movable or adjustable bell, means being provided for raising and lowering the same so as to regulate the passage of the products of combustion between the lower edge of the reflector and that of the bell.

Our present invention consists in an improved construction of the reflector, which is provided at one edge thereof with a damper, whereby the products of combustion, when the fire is first started, may be conveyed directly to the chimney or exit, while when the fire is well under way said damper may be closed, thereby compelling the products of combustion to pass between the lower edge of the reflector and that of the bell. The latter is supported, in the present case, by means of a spider resting upon the reflector, and it has no connection with the stove top or casing, thus enabling the top of the stove to be utilized for other purposes.

The invention, then, consists in the improved construction and novel arrangement and combination of parts, which will be here-

inafter fully described, and particularly pointed out in the claims.

In the accompanying drawings has been illustrated a simple and preferred form of embodiment of the invention, it being, however, understood that no limitation is necessarily made to the precise structural details therein exhibited, but that the right is reserved to any changes, alterations, and modifications to which recourse may be had without departing from the spirit or sacrificing the efficiency of the device.

In said drawings, Figure 1 is a perspective view of a stove equipped with the improved device, a part of said stove having been broken away for the purpose of exhibiting the construction of the attachment. Fig. 2 is a vertical sectional view. Fig. 3 is a horizontal sectional view taken on the line 3-3 in Fig. 2.

Corresponding parts in the several figures are indicated by similar characters of reference.

Referring to the drawings hereto annexed, 1 designates the casing of an ordinary stove, to which the invention has been applied. Internally in said casing near the top thereof and at suitable distances apart are provided lugs 2, which may be either cast upon the said casing or they may be bolted or otherwise secured thereto. These lugs serve to support the reflector 3, which latter is an annular casting having a flat side 4, which for convenience may be designated the rear side. With the exception of this flat side the side walls of the reflector converge downwardly, the upper portion of the reflector constituting a flange 5, upon which pairs of lugs 6 are formed or disposed to afford sockets for the arms 7 of a spider 8, having a central perforated hub.

The flange 5 of the reflector does not extend above the flat rear side 4; but the upper edge of the latter is provided with lugs 9, forming pivotal points for similar lugs 10, formed upon a damper 11, having a handle 12, which is adapted to extend through a suitable opening in the side of the stove-cas-

ing. When this damper is turned down, it forms a distinct continuation of the flange 5 at the upper edge of the reflector, so that the latter may be fitted closely within the walls 5 of the stove-casing.

While in the drawings a circular stove-casing has been shown and a correspondingly-constructed reflector, circular in horizontal section, it is obvious that the invention 10 may be applied to square or other shaped stoves by simply modifying the shape of the reflector to correspond.

14 designates a bell or bell-shaped casting, which is provided at its apex with an upwardly-extending bolt 15, extending through 15 the hub 8 of the spider 7 and there secured by means of a nut 16. Proper adjustment of the bolt with relation to the reflector may be had by interposing one or more washers, 20 as 17, between the nut and the hub. Beyond this initial adjustment it is found unnecessary to make further provision for the adjustment of the bell. The latter is provided at its lower edge with a flange 18, which extends 25 under the lower edge of the reflector, between which and said flange a sufficient opening must be left to insure the perfect operation of the device.

The flat rear side of the reflector is arranged 30 directly below the stovepipe 19, which, in the example illustrated in the drawings, has been connected with the top of the stove at the rear side of the latter. Here, again, it is to be understood that the invention 35 is applicable to stoves having differently-arranged smoke-exits, provided only that the flat side of the reflector is disposed conveniently below the smoke-exit.

In the operation of this device when a fire 40 is first built the damper 11 is thrown open, thus permitting the products of combustion to pass directly from the fire-pot to the smoke-exit. As soon as the fire is well under way the damper is closed and the products 45 of combustion will now pass into the highly-heated bell 14 and into the space between the reflector and the stove-casing. The soot, gases, and other products of combustion will be ignited while in contact with the highly-heated bell and reflector and will continue to burn, thereby igniting and consuming the products of combustion as they continue to rise, the necessary draft to maintain combustion being afforded by the narrow open 55 space between the lower edge of the reflector and the flange of the bell. The latter, as will be seen, extends perceptibly beyond the lower edge of the reflector, so as to obstruct the passage of products of combustion directly from the fire-pot, while the perfect 60 operation of the device is in no wise interfered with or retarded.

This device is, as will be seen, very simple 65 in construction and economical in use, effect-

ing a very considerable saving of fuel and avoiding the extremely-unpleasant black smoke usually escaping where soft coal is burned.

The device may be readily applied to 70 stoves of ordinary construction in the nature of an attachment, and the same is capable of being modified as to size, shape, and other minor points within the scope of the invention, so as to make it capable of such application as a stove attachment.

Having thus described the invention, what is claimed is—

1. The combination with a stove, of an annular reflector suspended within the stove-casing above the fire-pot, a bell supported within said reflector, and a damper connected hingedly with the reflector.

2. The combination with a stove, of an annular reflector supported within the stove-casing above the fire-pot, a bell supported within said reflector and provided at its lower edge with a flange projecting beyond and spaced from the lower edge of the reflector, and a damper connected with said reflector.

3. The combination with a stove, of an annular reflector supported in the stove-casing above the fire-pot, said reflector having a flanged upper edge lying in contact with the stove-casing, and a flat side, and a damper connected with the upper edge of the flat side, said damper forming, when closed, a continuation of the annular flange lying in contact with the stove-casing; the flat side of the reflector being disposed beneath the smoke-exit of the stove.

4. A reflector for stoves comprising an annular member having downwardly-converging walls and a flanged upper edge, said annular member having a flat side and a damper hinged at the upper edge of said flat side, in combination with a bell-shaped member supported within said annular member and having a flange extending beyond and spaced from the lower edge of the latter.

5. In a device of the class described, an annular reflector, having downwardly-converging walls, a spider mounted detachably upon said reflector, said spider having a central hub or bore, and a bell provided at its lower edge with a flange extending beyond and spaced from the lower edge of the reflector and having at its upper end a bolt extending through the bore of the spider and there secured adjustably.

In testimony that we claim the foregoing as our own we have hereto affixed our signatures in the presence of two witnesses.

BARRETT CLAUD. OBLINGER.
ALBERT HENRY CLAY BEATTY.
